US00D396724S

United States Patent [19]

Herbst et al.

[11] Patent Number: Des. 396,724

[45] Date of Patent: **Aug. 4, 1998

[54] RF AMPLIFIER FOR SATELLITE ANTENNA

[75] Inventors: Charles A. Herbst, Palm Bay, Fla.; Edoardo Varese, Cassina De'Pecchi, Italy; Rolando Ceccagno, Melzo, Italy; Massimo Boschetti, Concorezzo, Italy

[73] Assignee: Scientific-Atlanta, Inc., Norcross, Ga.

[**] Term: 14 Years

[21] Appl. No.: 58,884

[22] Filed: Aug. 27, 1996

[51] LOC (6) Cl. 14-03

[52] U.S. Cl. D14/230

[57] CLAIM

The ornamental design for a RF amplifier for satellite antenna, as shown.

DESCRIPTION

FIG. 1 is a top-side perspective view of a RF amplifier for a satellite antenna showing our new design;

FIG. 2 is a front elevational view thereof;

FIG. 3 is a rear elevational view thereof;

FIG. 4 is a left elevational view thereof;

FIG. 5 is a right elevational side view thereof;

FIG. 6 is a top plan view thereof; and,

FIG. 7 is a bottom plan view thereof.

FIG. 1

FIG. 2

FIG. 3
